(57) CLAIM

The ornamental design for a bracelet, as shown and described.

DESCRIPTION

FIG. 1 is a top plan view of a bracelet showing my new design; and,

FIG. 2 is a perspective view thereof, shown in use.

The broken line showing of an arm and the portion of a garment is for illustrative purposes only and forms no part of the claimed design.

1 Claim, 2 Drawing Sheets
